The ornamental design for a right hand hockey glove, as shown and described.

DESCRIPTION

FIG. 1 is a front elevational view of a right hand hockey glove, showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The undisclosed left hand glove is a mirror image of FIGS. 1-6 so as to fit a left hand rather than a right hand.
